[57] CLAIM

The ornamental design for a tennis score recorder, as shown and described.

DESCRIPTION

FIG. 1 is a front elevation view of a tennis score recorder showing my new design;

FIG. 2 is a back elevation view thereof;

FIG. 3 is a right side elevation view thereof, the left side elevation view being a mirrored image of the right side elevation view; and

FIG. 4 is a top view thereof, the bottom view being a mirrored image of the top view.

FIG. 1

FIG. 2

FIG. 3

FIG. 4
